UNITED STATES PATENT OFFICE.

PAUL HANSON, OF CHICAGO, ILLINOIS.

GRAIN-BINDER.

SPECIFICATION forming part of Letters Patent No. 602,445, dated April 19, 1898.

Application filed March 14, 1894. Serial No. 503,541. (No model.)

To all whom it may concern:

Be known that I, PAUL HANSON, a citizen of the United States, residing at Chicago, in the county of Cook and State of Illinois, have 5 invented new and useful Improvements in Grain-Binders, of which the following is a specification.

This invention relates to grain-binders, and particularly to the tripping and compressing 10 mechanisms; and its objects are to simplify and cheapen the construction of the same, to render it more effective in operation, and to adapt it to a wider range of use.

With these objects in view the invention 15 consists in the construction, combinations, locations, and relative arrangements of parts, as more fully hereinafter described, as shown in the accompanying drawings, and as finally pointed out in the appended claims.

20 In the drawings, Figure 1 is a view in side elevation of the end or binder deck side of a grain-binding machine, taken from the stubble side of the machine. Fig. 2 is an end view of the construction shown in Fig. 1.

25 Fig. 3 is a plan view, on an enlarged scale, showing the arrangement of my invention. Fig. 4 is a view in side elevation of the construction shown in Fig. 3 and showing in dotted lines a displacement of the parts from 30 their position as shown in full lines. Figs. 5, 6, 7, and 8 are detached detail views of various parts of my invention.

35 Referring to the drawings and to the various views and reference signs appearing thereon, and wherein similar reference signs refer to and designate similar parts wherever they occur throughout the several views, 1 designates the side plates or framework of the elevators, 2 the master-wheel, and 3 the frame- 40 work, of a harvesting-machine.

Supported by the framework of the machine is the housing or framework 4, in which are suitably journaled the needle-shaft 5, the knotter-operating shaft 6, and packer-shaft 7, 45 said packer-shaft and needle-shaft being arranged, preferably, in substantially the same horizontal plane or as nearly in the same horizontal plane as may be. Intermittent rotary motion is transmitted from the packer-shaft 50 to the knotter-operating and needle shafts by the following-described mechanism:

Upon packer-shaft 7 is mounted a gear 10,

adapted to mesh with a gear 9 upon an intermediate shaft 8. This intermediate shaft carries a sprocket-wheel 11. A corresponding 55 sprocket-wheel 12 is mounted on the knotter-operating shaft 6, and a sprocket-chain 13 connects said sprocket-wheels. Rotary motion is transmitted from the knotter-operating shaft to the needle-shaft by means of a 60 pitman 15 and crank-arm 16 in the usual way. An idler 14 serves to keep sprocket-chain 13 taut. Upon a stud 18, (see Fig. 7,) which is secured in the hub of gear 10, is pivoted the drive-dog 19. A spiral spring 22 rests at one 65 end against lug 21 on gear 10 and at the other end against lug 20 on the drive-dog and is held in place by pins or projections, as shown. This spring tends to rock the drive-dog upon its supporting-stud and thus throw the flange 70 or projection 23 thereon into the path of the rollers 24 24, carried by the continuously-rotated packer-shaft 7, as fully set forth in my Patent No. 510,174, granted December 5, 1893.

The upper end of the drive-dog is adapted 75 to be normally engaged by the end 26 of the trip-finger 27, whereby said dog is rocked in a direction opposed to the action of the spring to compress it, and thus hold the flange 23 out of the path of the rotation of the rollers 24 24. 80 Trip 27 is pivoted, as at 28, in a lug 29, cast on the usual housing or framework 4, and is provided with lugs 30 31, secured to said trip-lever or cast therewith. A rod or bolt 32 is pivoted in lug 30 and passes through a perforation in a lug 33, formed on housing or framework 4. A spiral spring 34 is coiled around bolt 32 and bears at one end against said lug 33 and at the other end against a nut 35, screwed on the threaded outer end of the 90 bolt 32. By adjusting nut 35 the tension of spring 34 can be adjusted. The tendency of spring 34 is to keep the end 26 of the trip-lever normally in position to engage the upper end of drive-dog 19, and by adjusting the tension of spring 34 the force required to overcome the action of the spring can be regulated, thus gaging the size of the bundle of grain. In order to provide a further means for regulating the size of the bundle, I provide a supplementary or auxiliary trip-finger 100 36, adapted to be attached, as at 37, to the trip-finger 27 between flanges 38 38, formed thereon, which prevent lateral movement of

said auxiliary finger, as will be readily understood. Upon the hub of the needle-arm is formed a cam 39. This cam is adapted to engage at the proper time in its rotation lug 31, formed on trip-lever 27, and thus keep the end 26 thereof elevated out of the path of drive-dog 19. Cam 39 is so formed that the end 26 is kept elevated a sufficient length of time for the various parts affected by the rotation of shafts 7 and 8 to perform their work. The operation of this part of my invention is as follows, the parts being in the position shown in Fig. 4:

The grain is fed down the binder-deck 59 and against compressor-hook 40 to form a bundle. When a sufficient quantity has been fed thereto, the trip-lever 27 is operated thereby by being tilted upon its pivotal support 28, thus elevating the rear end thereof out of engagement with the upper end of drive-dog 19. This movement is opposed by spring 34, which constantly tends to maintain lever 26 in position to engage said dog. The elevation of lever 26 causes said dog 19 to be tilted upon its pivotal support until flange 23 is in position to be engaged by one or the other of rollers 24 24, thus causing the rotation of gear 10, and consequently gear 9, intermediate shaft 8, knotter-operating shaft 6, and needle-shaft 5. During the rotation of these shafts the bundle of grain is compressed, tied, and ejected from the machine. As needle-shaft 5 begins to rotate cam 39 comes into position to engage lug 31 and prevents arm 26 from descending into position to again lock drive-dog 19 until a complete oscillation of the needle-shaft has been effected and the needle has returned to its normal position and the bundle ejected. When these operations have been completed, the part of cam 39 is reached where spring 34 operates to force bar 26 into position to lock drive-dog 19 from further rotation.

Reference - sign 40 designates the compressor-hook. This hook is secured in slot 41 of compressor-bar 42, whereby it may be adjusted to regulate the size of the bundle of grain. Compressor-bar 42 is carried by compressor-shaft 43, journaled to rock in lugs 44 44, cast on housing 4, or the compressor-bar may be pivoted concentric with the needle-shaft, as will be obvious to any one skilled in the art. To the outer free end of the compressor-bar is pivoted an internally-screwed threaded sleeve 45, adapted to receive the screw-threaded end of a preferably-squared bolt 46, adapted to pass through a perforation in the end of a rock-lever 47, sleeved on binder-pipe 48. A spring 49 is coiled around bolt 46 and bears at one end against the perforated end of the rock-lever 47 and at the other end against a collar on sleeve 45. The tendency of this spring is to keep compressor-bar 42, and with it compressor-hook 40, elevated into position to engage the grain as it is delivered thereto and arrest its feed until a sufficient quantity has been arrested to be

tied into a bundle. The spring 49 keeps said hook elevated against a yielding resistance, and by screwing bolt 46 into and out of its threaded socket 45 the tension of the spring can be regulated, and also the elevation of compressor-hook 40 may thus be regulated. Thus an additional adjustment is provided for the regulation of the size of the bundle. An arm 50 is formed on or carried by the other end of the sleeve, forming the hub of arm 47, and the free end of said arm is adapted to be projected into the path of rotation of a cam-flange 52, carried by wheel 53, mounted to rotate upon a stud or bolt 54. This wheel may be rotated in any suitable way. In the form shown this is a star-wheel, and mounted upon the face of gear 9 are pins 55 55, adapted when said gear is rotated to enter the space between the points of the star of star-wheel 53 (see Fig. 6) and rotate the said star-wheel step by step. The part 57 of the points of the star-shaped wheel is adapted to slide against the flanged hub 56 of gear 9, and thus hold the same locked against further rotation until again operated by studs 55 55. The operation of this part of my invention is as follows: The parts being in the position shown in Fig. 4, except that the end 26 of trip-lever 27 is elevated, thus permitting rotary motion to be imparted to gear 10, and consequently to gear 9 and the knotter-operating and needle shafts, as gear 9 rotates in the direction of the arrow, Fig. 4, the lower pin or stud 55, projecting from the face thereof, enters a space in gear 53 and rotates it one step. In the position shown cam-flange 52 is in engagement with a flange 58, Fig. 6, upon rock-arm 50, thus holding the arm 47 raised, and consequently the compressor-bar 42 and hook 40 are solidly supported against a yielding resistance due to spring 49. The further rotation of gear 53 causes cam-flange 52 to ride over the friction-roller on the end of arm 50, thus rotating the parts above mentioned to their extreme elevated position. During this time the bundle of grain is being formed and compressed against compressor-hook 40, and consequently the greatest pressure is being exerted against said hook during the latter part of the engagement of the cam-flange 52 with arm 50—that is, while the knot is being tied. When cam-wheel 53 is rotated until the end of the cam-flange rides off of the end of arm 50, said arm is permitted to rise, thus permitting the rock-lever 47, compressor-bar 42, and compressor-hook 40 to fall into the position shown in dotted lines, Fig. 4, until the upper end of the compressor-bar 40 falls below the surface 59 of the binder-deck, thus permitting the bundle to be ejected from the machine. Further rotation of gear 53 brings the cam-flange 52 again in contact with flanged arm 50 and again elevates the compressor-hook 40 into position to assist in compressing another bundle of grain. The relative sizes of gears 9 and 12 are so proportioned that it requires three rotations of gear 9 to ef-

fect a complete revolution of the knotter-driving shaft, and hence of the needle-shaft. It is consequently essential that gear 53 be given only one complete revolution during a complete revolution of the knotter-operating shaft in order that the operation above described will take place once during each complete revolution of said shaft, and while I have described a specific form of gearing for rotating the gear 53 once during these revolutions of gear 9 I do not desire to be limited thereto, as many other forms of mechanism may be employed whereby the same result may be accomplished.

15 In order to support the housing or framework carrying the above-described mechanisms in such manner as to permit of longitudinal adjustment thereof, I provide a pivoted or hinged bracket 60, provided with pintles 20 61 62, adapted to be received in suitable perforations or sockets in framework 3 of the harvester-machine. The outer portion of housing 4 is provided with a saddle 63, adapted to rest on the outer portion of the upper or horizontal leg of the hinged bracket. The space 25 in said saddle to receive the bracket is made of sufficient size to permit a relative movement of the housing and bracket, so that when said housing is adjusted longitudinally, 30 along its support on the framework 3 the bracket will be permitted to rock upon its pivots 61 62. One important advantage attained by the provision of this bracket aside from its simplicity, cheapness, and efficiency is that 35 the binder-pipe 48 may be considerably shortened, thus reducing the cost and weight of the attachment. Many other advantages are secured by this construction, which will be readily understood and perceived by persons 40 skilled in the art.

In order to guide and steady the housing 4 in its longitudinal adjustment upon framework 3, the cross-bars or sills 64 are formed to fit flanged bar 66, (see Fig. 8,) and a cap- 45 plate 65 assists in forming a guide for said flanged bar, as will be readily understood.

It is important that the moment end 26 of the trip-lever engages the upper end of drive-dog 19 to throw the flange 23 thereof out of 50 the path of travel of rollers 24 24 on the packer-operating shaft 7 the reverse rotation of gear 10 be avoided in order to lock the train of gearing driven thereby against retrograde movement. It will be readily understood that 55 by arresting the rotation of trip-dog 19 the action of spring 22 will be to rotate the gear 10 in a reverse direction through its engagement with lug 21. In order to avoid this difficulty, I provide the following-described stop 60 or locking devices: Upon cross-bar or sill 67 I pivot a dog or trip 68 intermediate its ends. A spring 69 is provided to bear against one end thereof to keep the same elevated (see Fig. 4) and which normally keeps the other end of 65 said dog depressed. This dog is pivoted to cross-bar or sill 67, adjacent to the bearing for the end of the packer-operating shaft and

adjacent to gear 10, mounted on said shaft. Said gear is provided with a projection or rib 70, which in the form shown is formed by extending rearwardly a tooth thereof. (See Fig. 3.) This projection rotates in a path to engage and lift the outer end of dog 68 against the action of spring 69; but when drive-dog 19 is locked by lever 26 against further rotation, and consequently when the rotation of gear 10 ceases, the front end of dog 68 falls into position behind the projection 70 and effects a locking of said gear against a reverse or retrograde movement.

75 To limit the rocking of compressor-bar 42, said bar is provided with projections 71 72, adapted to strike the hub of the needle-arm, or it may be constructed to strike a portion of the main frame or housing 4 when the extreme limit of movement of the compressor-hook is reached in the direction in which it may be rocked.

80 Many changes may be made in the details of construction of my invention without departing from the spirit or scope thereof, and I do not desire to be limited to the exact and specific details shown and described; but

85 What I do claim as my own invention, and desire to secure by Letters Patent of the United States, is—

1. In a grain-binder and in combination with a needle-shaft and needle, of a pivoted compressor-bar, a compressor-hook carried thereby, a lever arranged beneath the binder-deck and pivoted intermediate its ends below and adjacent to said needle-shaft, connections between one arm of said lever and said compressor-bar, a gear-wheel having a cam-flange adapted to engage the other arm of said lever, means for rotating said flanged wheel periodically, comprising a gear having pins adapted to engage teeth on said flanged gear, and means for locking said flanged gear during its period of rest; as and for the purpose set forth.

100 2. In a grain-binder and in combination with the needle-shaft and needles and gearing for operating the same, of a compressor-bar, a lever arranged beneath the binder-deck, 105 and pivoted intermediate its ends below and adjacent to said shaft, spring connections between one arm of said lever and said compressor-bar for yieldingly supporting the latter, and means, also arranged beneath the binder-deck, for periodically engaging and releasing the other end of said lever, comprising a flanged wheel, a gear having spaced pins projecting from the face thereof, arranged to engage teeth on said flanged wheel, 110 and formed with a flanged hub adapted to engage the periphery of the teeth on said flanged wheel to lock the same during its period of rest, and means for operating said pin-wheel; as and for the purpose set forth.

115 3. In a grain-binder a star-shaped gear having a cam-flange thereon, a drive-gear therefor and means for rotating the same, pins and a flanged hub carried by said drive-gear said

- pins adapted to engage the star-shaped gear and impart a step-by-step rotary motion thereto, the periphery of the points of the star-shaped wheel adapted to engage said flanged hub and to be locked against rotation during the periods of rest thereof, in combination with a bell-crank lever, a pivoted compressor-bar and adjustable spring connections between said bar and lever as and for the purpose set forth.
4. In a grain-binder a packer-shaft and means for rotating the same, a needle-shaft and gearing intermediate said shafts for rocking said needle-shaft, a tripping mechanism for periodically throwing said intermediate gearing into and out of action comprising a pivoted trip-lever and an auxiliary or supplementary finger secured to said trip-lever, as and for the purpose set forth.
5. In a tripping mechanism for a grain-binding machine a pivoted trip-lever provided with flanges in combination with an auxiliary finger adapted to be secured thereto between said flanges, as and for the purpose set forth.
6. In a grain-binding machine, a framework, a housing, gearing, packing, knotting and compressing mechanisms, said housing supported at one end by said framework,

means for adjusting said housing along said framework, a support for the outer end of said housing, provided with an open face, constituting a saddle, a bracket pivotally supported on the harvester-framework and extending outwardly therefrom, and adapted to receive said open-faced saddle to support said housing, whereby said bracket may be rocked about its pivots and move in said saddle when said housing is adjusted in a straight line along said harvester-framework; as and for the purpose set forth.

7. In a grain-binding machine a framework, having a hinged bracket, a housing supported at one end by said framework, an open-sided casting carried by said housing at the opposite end thereof, adapted to rest on and be supported by said hinged bracket, whereby said hinged bracket may be rocked to permit adjustment of said housing upon said framework in a straight line; as and for the purpose set forth.

In testimony whereof I have hereunto set my hand, this the 10th day of March, 1894, in the presence of two subscribing witnesses.

PAUL HANSON.
